(57) **CLAIM**

The ornamental design for a hanger assembly for use with panel awnings, as shown and described.

DESCRIPTION

FIG. 1 is a front view of a hanger assembly for use with panel awnings showing my new design;

FIG. 2 is a back view thereof;

FIG. 3 is a side view; opposite side view is a mirror image thereof;

FIG. 4 is a top view;

FIG. 5 is a bottom view; and,

FIG. 6 is a perspective view thereof.

1 Claim, 3 Drawing Sheets

FIG. 6
